UNITED STATES PATENT OFFICE.

WILLIAM M. SMITH, OF WEST MERIDEN, CONNECTICUT, ASSIGNOR TO THE MERIDEN BRITANNIA COMPANY, OF SAME PLACE.

DESIGN FOR COFFIN-SCREW HEADS.

Specification forming part of Design No. 7,798, dated October 13, 1874; application filed September 30, 1874.
[Term of Patent 7 years.]

CASE B.

To all whom it may concern:

Be it known that I, WILLIAM M. SMITH, of West Meriden, in the county of New Haven and State of Connecticut, have invented a new Design for Coffin-Screws; and I do hereby declare the following, when taken in connection with the accompanying drawings and the letters of reference marked thereon, to be a full, clear, and exact description of the same, and which said drawings constitute part of this specification, and represent, in—

Figure 1, a side view; and in Fig. 2, a top view.

This invention relates to a design for the heads of screws, such as are used for securing the top of coffins, and known as coffin-screws; and the invention consists in the formation of a wing upon each side of a substantially cylindrical head.

From the base *a* of the head the screw *b* projects downward, and upward from the base the body *A* rises, preferably of an urn or cylindrical ornamental shape. Upon opposite

sides a wing or flange, *d*, projects, giving appearance of handles upon the urn or ornament. These wings, while adding to the appearance of the head, also possess a certain degree of utility, inasmuch as a cylindrical head is with difficulty turned. The wings *d* afford a bearing for the thumb and finger, to more readily exert the requisite power to turn the head.

The shape of the urn may be varied, according to the taste of the manufacturer or demands of the trade, the essential feature of the design being the projecting handles or wings *d*.

I claim—

The herein-described design for coffin-screw heads, consisting of the cylindrical or urn shaped head with a wing, *d*, projecting from opposite sides, as herein described and shown in the accompanying illustration.

WILLIAM M. SMITH.
